APPARATUS FOR UNINTERRUPTED RE-
PRODUCTION OF DISK PHONOGRAPH
RECORDS

Robert E. Stanton, Denver, Colo.

Application May 15, 1945, Serial No. 593,817

5 Claims. (Cl. 179—100.4)

1

This invention relates to improvements in phonographs and has reference more particularly to an improvement by means of which an ordinary automatic phonograph can be made to play a series of records without interruption, and the entire assembly will be designated herein as a continuous phonograph.

It is the object of this invention to produce an attachment in the nature of a sound recording and reproducing device that can be attached to any automatic phonograph for the purpose of converting it into a continuous phonograph in which the sound will not be interrupted due to the changing of the records.

Lengthy musical compositions, such as opera scores, concertos and symphonies often require many standard size records (either 10 or 12 inch) that are to be played in regular sequence. Such records usually have recordings on both sides. When an ordinary automatic phonograph is employed, there is a break in the continuity while the record is turned and also when another record is substituted.

It has been found that an ordinary automatic phonograph requires about fifteen seconds for the operation of turning, or, for the changing of a record. The auxiliary transcribing device which forms the subject of this invention will continue the music during this time interval, thereby providing an uninterrupted rendition.

My invention, briefly described, and in its broadest aspect, consists in interposing in the circuit between the electric tone arm of the automatic phonograph and its loud speaker, a device which will record the sound waves, corresponding to the record being played, onto another record and transmit them to the loud speaker at a sufficiently reduced tempo to lengthen the sound reproduction period sufficiently to cover the gap of fifteen seconds necessary for changing the records on the phonograph.

My attachment, in its present embodiment, comprises a sound recorder and transcriber of the type known as the "Poulsen telephone," which is connected with the electric pickup on the tone arm of the phonograph in such a way that a steel wire becomes magnetized in a manner corresponding to the sound waves. An electric pickup of a type that responds to variations of the magnetism of the wire, generates an electric current which is then subjected to amplification and transmitted to the loud speaker. The attachment or auxiliary transcriber is so constructed that it will continue the operation of the loud speaker for about fifteen seconds after the

2

playing of the original record has been completed. The auxiliary attachment for at least a period of the time, records and reproduces the music at a slower tempo than the original thus prolonging the sound some time after the original record has been played.

Although a transcriber of the telephone type will be used for explaining the invention, it is evident that a transcriber employing a disk record can be used.

In order to describe the invention so that its construction, mode of operation, and its relation to the original phonograph can be readily understood, reference will be had to the accompanying drawings in which the invention has been illustrated, and in which:

Figure 1 is a diagram showing the general arrangement and relationship of the several elements;

Figure 2 is a perspective view of the transcribing attachment, parts being broken away to better disclose the construction;

Figures 3 and 4 are diagrams for use in describing and explaining the operation;

Figures 5 and 5a are views illustrating the construction of the magnet poles employed;

Figure 6 is a diagram illustrating means for preventing a new record from being started by the phonograph until the record on the transcriber is finished;

Figure 7 illustrates a means for automatically changing the motor speed; and

Figure 8 is a diagram showing one means for retarding the speed shifting mechanism to compensate for the time element due to the relative movement of record 12 and recording magnet 9.

Reference will now be had to the drawings and to the several figures thereon where the various elements have been designated, either by reference characters, or by numbers.

In Figure 1 the several elements of this machine have been indicated in a general way. The automatic phonograph has been designated by P; the series of records by R; the tone arm by TA; the tone arm amplifier by TAA; the transcriber by T; the power amplifier by PA; the loud speaker by L; and the momentary contact switch by SWX. Since electronic amplifiers are old and well known, the specific arrangement and/or the circuits have not been shown. The transcriber has been illustrated in Figure 2 to which reference will now be had.

Reference numeral 1 designates a base on which is supported a frame having at least two upright members 2 and a transverse member 3. A shaft

4 is journalled in bearing 5 on the base and in bearing 6 in the transverse member. Surrounding this shaft is a tubular shaft 7 that carries an arm 8 to the end of which is secured a recording magnet 9. A sound record 10 is carried by the upper end of shaft 4 and comprises a cylinder 11 of non-magnetic material such as aluminum or copper, or some suitable synthetic, preferably a nonconductor of electricity. Embedded in the cylinder is a wire helix element 12 formed from a magnetizable material such as hardened steel. A motor 13 is supported on the base and is connected by means of a reducing gear 14 with shaft 15. Socket 16 is secured to shaft 17 and shaft 15 is slideable, but nonrotatably connected therewith. Shafts 15 and 17 are journaled, respectively, in the upright frame members 18 and 19. Shaft 4 carries two gears 20 and 21, which are concentric and of different sizes, as shown in the drawing. A gear 22 is nonrotatably connected with the lower end of tubular shaft 7. Shaft 17 carries pinions 23 and 24. In the position shown in the drawing, pinion 23 meshes with gear 22 and pinion 24 with gear 20. Shaft 17 carries a spool-like member 25 between the flanges of which are positioned fingers 26, comprising the lower end of the downwardly projecting fingers 27 of the bell crank lever. The bell crank lever is pivoted at 28 and has a horizontal arm 29 that extends to both sides of the pivot so as to form with arm 27 an unsymmetrical cross. When the bell crank lever is rotated in a counterclockwise direction, it moves pinion 24 into engagement with gear 21 and disconnects pinion 23 from gear 22, whereupon tubular shaft 7 stops rotating. While pinions 23 and 24 and gears 20, 21 and 22 have been shown as provided with teeth, a suitable friction gear may be substituted if found desirable. A worm 30 is secured to the tubular shaft and engages a gear 31 on shaft 32. A disk 33 is carried by shaft 32 and has a notch 34 for the reception of arm 29. Whenever notch 34 gets into position directly above this arm, the bell crank arm 29 moves into the notch and shifts the gears as above explained.

It will be observed that pinions 23 and gears 22 and 20 produce relative rotation of shafts 4 and 7 in opposite directions. For the purpose of this description the record 10 will rotate in a counterclockwise direction, as indicated by the arrows, and recording magnet 9 will rotate in the opposite direction but at a much slower speed. Secured to one of the frame members 2 is a bracket 35 that carries a takeoff magnet 36 and an eraser magnet 37. Carried by the tubular shaft are two slip rings 38 to which the ends 39 of the soleil winding on the recording magnet are connected. Brushes 40 contact with the slip rings and these in turn are connected to terminals 41 by means of wires 42. A magnet 43 is supported on the transverse frame member 44. A plunger armature 45 is associated with magnet 43 and has a slotted opening for the reception of the short end of arm 29. When magnet 43 is deenergized, the weight of the armature rests on the arm 29 and urges the long end of this arm upwardly against disk 33; and therefore whenever slot 34 gets into position above arm 29, the bell crank lever will rotate in a counterclockwise direction and move pinions 23 and 24 out of engagement with gears 22 and 20 and move pinion 24 into engagement with gear 21, whereupon arm 8 and the recording magnet will cease to rotate and shaft 4 will rotate at a slower speed. This takes place when the recording magnet is above the inclined extension 46 of plunger 45 in the posi-

tion indicated by A in Figures 3 and 4. When magnet 43 is energized, in a manner to be hereinafter explained, it moves the plunger and the inclined end portion 46 upwardly, thereby returning pinions 23 and 24 to the position shown in drawing and at the same time 46 moves the recorder magnet 9 to a point beyond the takeoff magnet 36 and the eraser magnet 37 indicated by B in Figures 3 and 4.

Both the record 10 and the recording magnet 9 will now rotate and will continue to rotate at different speeds until disk 33 has made one complete turn, whereupon the recording magnet will stop in a position close to the eraser magnet 37, (see Fig. 3) shown dotted in Figure 2. The length of time that recording magnet 9 rotates is dependent on the speed ratio of the worm gear (30, 31) and it may make several complete revolutions before notch 34 reaches a position above 29. The relative speeds at which 9 and 10 rotate and the number of revolutions made by the recorder magnet 9 determine the increased distance traveled by the record 10 relative to the recorder 9 over what this distance would have been if recorder 9 had remained stationary and this in turn determines the time the transcriber will continue to play after recorder 9 becomes inactive. This time interval must be long enough to permit the automatic phonograph to change records which is about fifteen seconds.

In Figure 3 an attempt has been made to illustrate the several positions. A shows the stationary position of the recorder 9 after lever arm 29 has moved into notch 34 and until magnet 43 is energized causing cam 46 to move the recorder from position A to position B. The number of complete turns that the recorder 9 makes while disk 33 makes one complete revolution determines the extent to which the record has been lengthened and the time it will continue to play after recorder 9 becomes inactive.

It will be observed that record 10 will be lengthened, due to the movement of the recorder magnet 9, in the opposite direction from that of record 10, and therefore the music or other sound will have a slower tempo than that of the master record on the phonograph. This is necessary in order to gain the time necessary for changing the record on the phonograph. That part of record 10 that is recorded after the recorder 9 has stopped in position A will have the same tempo as that of the master record. It is now apparent that unless some means is provided to prevent it, the music will be reproduced at two different tempos.

Practically all makes and types of automatic phonographs operate at a turntable speed of 80 R. P. M. which permits an ordinary 10-inch record to be played in from two and one-half to three minutes. The transcriber lengthens the time about fifteen seconds and in order to produce an audible rendition at the original tempo of that part recorded while the recorder 9 moves, the speed of the phonograph turntable must be increased during this period or else record 10 must be rotated at a slower speed until recorder 9 stops and then at a higher speed; in the example given, this construction has been shown.

Referring to Figure 2, it will be observed that as long as shaft 7 turns, pinion 24 is in engagement with gear 20, but as soon as the pinions are shifted to disengage pinion 23 from gear 22, pinion 24 will move into engagement with the smaller gear 21 and increase the speed of shaft 4. In the drawing the gears have been shown more

or less diagrammatically, but it is to be understood that the gear ratios must be carefully calculated and proper gears used.

Another way to obtain the same result would be to shift pinion 23 only and omit gear 21 and to provide means for increasing the speed of the motor 13. Such an arrangement has been shown diagrammatically in Figure 7 where the electric circuit to the motor has been provided with a selective two-speed drive element 47 which is controlled by a switch 48, that is opened and closed by an arm 49 secured to the core 45, or to the end of lever arm 29. When switch 48 closes the speed of the motor 13 will be reduced or increased as the case may require.

In place of changing the speed of motor 13, it is possible to run the motor of the automatic phonograph somewhat higher during the time that recorder 9 rotates and to reduce this speed to normal when lever 29 moves into notch 34.

It is, of course, understood that both the recorder magnet and the takeoff magnet have laminated cores so as to reduce the hysteresis and the resultant magnetic lag and heat to a minimum. Cores and other parts made from compressed, powdered iron or any other suitable material may be used.

It is evident that the several magnets must be provided with specially constructed pole pieces for the purpose of following the spirals of the magnetizable wire record 12; the construction adopted for this purpose will now be described and reference for this purpose will be had to Figures 5 and 5a.

Referring now to Figure 5, which is partly in section, the core has been designated by 50 and this terminates in a triangular end 51. Three pulleys 52 have been mounted for rotation on pivots 53. A chain 54 comprising a series of hingedly connected links, encircles the pulleys. Pole pieces 55 are attached to the chain and spaced equidistantly thereon, as shown more clearly in Figure 5a from which it will be seen that the opposite interior base angles are somewhat smaller than those shown in Figure 5. The cylindrical wall of record 10 in which the wire helix 12 is embedded, is provided on both sides with spiral ridges 56. Pole pieces 55 have their ends provided with curved notches that fit about the ridges 56 and therefore when record 10 turns relative to the pole pieces, the latter will move downwardly. The parts are so proportioned and arranged that before the lower pole piece leaves the record, the upper one will be in position. The number of turns of wire 12 between the pole pieces 55 must be of sufficient length to record a 12-inch record. This is, however, not an essential requirement as will later appear. Pole pieces 55 on the pickup magnet 36 and the eraser magnet 37 engage the same spiral ridge a few inches apart whereas pole piece 55 on recorder magnet 9 may engage a ridge spaced several turns away. Whenever recorder 9 is in position B it must be on the same helical coil as 36 and 37.

In Figures 3 and 4 the pole pieces have been shown pointed in order to simplify the drawing. It is to be understood that the poles must be of such construction that they will follow the spiral ridges.

All records are not of the same length even when of the same diameter. The last record, especially of a series, is likely to be shorter than the others; any one or all of the records of a series may be of different length. Unless means is provided for preventing such an occurrence,

the automatic phonograph, after having played a record of average length followed by a shorter record, would change records and begin to play another before the transcriber had completed playing the short record. In any event, it is evident that the phonograph must not begin playing a new record until the transcriber has finished with the previous one.

In Figure 6 means has been illustrated for preventing the next record from overlapping the previous one.

Referring back to Figures 1 and 2, it will be observed that a normally open switch *SwX* is positioned underneath the tone arm in position 15 to be engaged and closed when the tone arm is moved into operative position by the automatic mechanism. In Figure 2 the same switch has been shown as controlling the flow of current from a source of electric current supply, such as 20 the battery *Ba*, to the magnet 43. As soon therefore as the tone arm *TA* is moved into operative engagement with the record on the turntable, magnet 43 is energized and cam 46 moves the recorder magnet 9 from position A to position B 25 (Figs. 3 and 4) and the recorder begins at once to magnetize wire 12 in accordance with the new record. It is necessary that no new recording be made on wire 12 until the last notes have passed the pole of recorder magnet 9 when in position B.

In order to prevent overlapping of magnetic recordings on wire 12, the following means have been provided.

Referring now to Figure 6, it will be noted that 35 a magnet 58 has been positioned adjacent the pickup magnet 36 in position to have a current induced in its winding when the magnetized record 12 passes its pole. The terminals of the winding of magnet 58 are connected by wires 59 and 60 to a relay 61 that is held in open position as long as a current is flowing through wires 59 and 60. Such relays are available and the construction has therefore not been illustrated.

A lever 62 is pivoted to the tone arm at 63; one 45 end is bent downwardly and provided with a roller 64 positioned to engage the upper surface of a record. The other end of lever 62 extends upwardly as indicated at 65. A magnet 66 is carried by the tone arm adjacent its pivoted end and this has an armature 67 pivoted at 68 and held in such a position by a spring 69 that the end of arm 65 will engage it and thereby hold the tone arm in such position that the pickup needle can 50 not come into engagement with the record. When the erased portion of wire 12 reaches a point under the pole of magnet 58, no current is induced in the winding and relay 61 closes, thereby energizing magnet 66 which attracts armature 67 and releases lever 62, permitting the tone arm 55 to drop and place the pickup needle into engagement with the record. When electromagnet 66 is energized and the tone arm drops into operative position, switch *SwX* closes and energizes magnet 43, moving recorder 9 from position A to 60 position B and shifting pinions 23 and 24 into the position shown in Figure 2, whereupon a new record will be recorded on wire 12 and transcribed into music or sound.

It is, of course, understood that the automatic phonograph is silent and merely serves to transfer the sound recorded thereon onto the wire 12 from which magnetic record the magnetic variations thereon are translated into a variable current by pickup magnet 36. This current is am-

plified by the power amplifier PA and transmitted to the loud speaker.

The operation of the device is as follows: A number of records R which are to be played in succession are arranged in order in the automatic phonograph. The several elements are connected as shown and described. The current generated by the electric pickup on the tone arm of the phonograph energizes the coil on magnet 9 and the pole 55 of the latter magnetizes wire 12. When the magnetized portion of wire 12 passes the pole 55 of pickup magnet 36, a current is induced in its winding and this is amplified and transmitted to the loud speaker. Magnet 37 which is energized by a constant direct current, erases the magnetic record from wire 12 immediately after it has served its purpose in connection with magnet 36. Recorder magnet 9 moves in the opposite direction to wire 12 and gradually increases the length of wire between its pole and that of magnet 36 until the distance will result in a playing time of about fifteen seconds or sufficient for the automatic phonograph to change records. The recorder magnet then stops until another record is to be recorded.

Means have been described for correcting for the slower tempo that results from the movement of magnet 9 during a portion of the recording, and for correcting the speed of the phonograph turntable or of the record 10 to maintain the original tempo, both during the time magnet 9 moves as well as when it stands still. Means comprising switch SwX and magnet 43 shifts the position of magnet 9 at the beginning of each record and means has also been provided for preventing overlapping of recordings on wire 12.

It is evident that specifically different mechanisms may be used and it is even possible to replace the telephone type of transcriber by one using ordinary records and applicant therefore considers that his invention embraces the combination disclosed regardless of the form and/or construction of the various elements so long as the elements perform the same function in substantially the same way.

Since practically all records manufactured are intended to be used with phonographs whose turntables rotate 80 R. P. M. the normal tempo of such records is attained only when they are rotated at this speed. If the record is rotated at a higher speed than this, the tempo will be above normal and vice versa.

It is evident that the music or sound emitted from the loud speaker must have normal tempo. Since the music or sound must be recorded on the transcriber record at a lower tempo than that corresponding to the speed at which the record is turning, it follows that for the period that the recorder 9 moves in a direction counter to that of record 10, the turntable of the phonograph must rotate sufficiently above the normal speed to produce a normal tempo of the transcribed music. To accomplish this the phonograph motor must be speeded up during the time that the record 9 is rotating and reduced to normal speed when the record stops. Means for accomplishing this is shown in Figure 7.

The invention has been illustrated and described in connection with a device for reproducing sound. It is to be understood that protection is desired for any and all uses to which the invention can be put. If it is found that the device can be used for television or any other purpose requiring the reproduction of electric cur-

rents having special wave forms and frequencies, such use is contemplated.

The magnetizable wire helix may be formed from any suitable material that can be magnetized and which will retain its magnetism for a sufficient length of time to effect the results desired. Certain kinds of steel are suitable and in addition such alloys as are now used for making permanent magnets.

10 It has been pointed out that the sound waves which are transcribed upon the electromagnetic record during the normal transcribing speed, which is an additive result of the drum speed plus the rate of the recorder magnet advance, will be delivered into the takeoff element at higher tempo during a brief interval immediately following the arresting of the recorder magnet and the shifting of the drum speed at the conclusion of a predetermined period.

15 At this time, the relationship of the various elements will be substantially as shown in Figure 4, when the recorder 9 is shown in position A, and approximately one full turn of the record wire 12 separates the recorder 9 from the takeoff magnet 3.

20 Assuming the normal rotating speed of the drum to be 80 R. P. M., this increased tempo may result in distortion of the sound rendition for approximately $\frac{1}{80}$ of a minute until the portion of the electromagnetic record, properly 25 adjusted to the increased drum speed, reaches the takeoff magnet 3.

At this time, the relationship of the various elements will be substantially as shown in Figure 4, when the recorder 9 is shown in position A, and approximately one full turn of the record wire 12 separates the recorder 9 from the takeoff magnet 3.

25 For the purpose of preventing a sudden change in tempo when the recorder magnet stops at point A the change in speed of the record 12 must remain the same until the point on record 12 reaches the pickup magnet 36, which should be approximately fifteen seconds. In Figure 8, a slight modification has been shown in which pinion 24 is of considerable width and in which the longitudinal movement of shaft 17 is controlled by a dashpot 70. A lever 71 is pivoted at 30 72 and has a portion engaging the groove in spool 25, so that it will turn about its pivot when shaft 17 moves longitudinally. The free end of lever 71 projects between two spaced pins 73 on the piston rod 74 of the dashpot. The distance between pins 73 is greater than the width of lever 71 to provide a lost motion connection. Shaft 17 can move towards the right a sufficient distance to disengage pinion 23 from gear 22 before the dashpot becomes effective. Pinion 24 is quite wide as shown and the parts are adjusted so that it will take approximately fifteen seconds for pinion 24 to disengage gear 20 and engage gear 21.

35 The above is merely illustrative of means for this purpose and any mechanical equivalent can be substituted.

Having described the invention what is claimed as new is:

40 1. A mechanism for playing records in sequence, comprising: means for rotating a record at a predetermined constant speed, an electric pickup operatively associated with a record adapted to be carried by the record rotating means, a sound recording device operatively connected with the electric pickup, means translating the sound recordings into an electric current having amplitude and frequency characteristics corresponding to the recorded sound, an electrodynamic loud speaker, means transmitting current from the translating means to the loud speaker including an electronic amplifier, said sound recording device including recording means, 45 an element upon which the recording means

records the sound, the recording means and translating means being relatively movable with respect to said element, the rate of relative movement of the recording means being greater than that of the translating means whereby a predetermined rate of decrease in the tempo of the sound emitted by the loud speaker relative to that of the record is effected, to obtain a time lag, and the loud speaker as a result of said decrease in tempo will continue functioning a sufficient time after the electric pickup and recording means become inoperative, to provide sufficient time to change to another record of the sequence.

2. In a continuously playing phonograph having a turntable adapted to carry records in sequence, a tone arm carrying an electric pickup device operatively associated with a record carried by the turntable, means for rotating the turntable at a predetermined constant speed, and means for lifting the electric pickup from the record and for replacing a played record with another; means translating electric current generated by the pickup into audible sound waves comprising a sound recording device including a movable magnetizable wire operatively associated with the electric pickup by means of a recorder magnet operatively associated with the movable magnetizable wire, means for translating the recordings on the wire into a variable electric current having the same wave form and amplitude characteristics as the current generated by the pickup, comprising a take-off magnet operatively associated with the wire record, means for translating the current generated in the takeoff magnet into audible sound, comprising an amplifying device and a loud speaker operatively associated with the take-off magnet, and means for progressively increasing the distance between the recorder magnet and the take-off magnet along the wire to decrease the tempo of the current in the take-off magnet relative to that in the recorder magnet.

3. A continuously playing phonograph comprising, a turntable, a sound record supported thereon, an electric pickup operatively associated with the record, means for rotating the turntable and record at a predetermined constant speed, a helical coil of magnetizable wire, a base on which the coil is supported, means rotating the coil about its axis, a recorder electromagnet carried by the base, said magnet having a pole positioned adjacent the wire whereby the latter will be magnetized in response to variations in the magnetic flux from the pole, means varying the magnetization of the pole in accordance with the variations in intensity, frequency and characteristics of the current generated by the electric pickup, comprising an electronic amplifier in a circuit interposed between and operatively connected with the recorder electromagnet and the electric pickup, a take-off electromagnet positioned with its pole in inductive relation to the wire, the last named electromagnet being stationary relative to the frame, means for moving the first named magnet in a path parallel to the wire in the direction opposite to that which the wire travels but at a slower speed whereby the space between the two magnets will gradually increase, an electromagnetic loud speaker, means comprising a circuit in series with the magnet windings of the

take-off magnet and of the loud speaker and an electronic amplifier in the circuit, for operating the loud speaker, whereby the variations in the magnetism of the wire will be translated into sound waves, and an eraser magnet operatively associated with the take-off magnet and the wire, and spaced from the latter in the direction of wire travel.

4. A continuous phonograph comprising, a continuously rotating turntable, a sound record supported thereon for rotation therewith, an electric pick-up operatively associated with the record, a continuously moving magnetizable wire record, a recorder magnet of the telephone type positioned in operative relation to the wire, means including an amplifying device and circuit connections for energizing the recorder magnet by current from the pick-up, a take-off magnet positioned in operative relation to the wire record, a sound reproducing device, a circuit including a power amplifier connecting the take-off magnet with the sound reproducer, and means for progressively increasing the distance between the recorder magnet and the take-off magnet along the wire to progressively decrease the tempo of the sound emitted by the sound reproducing device relative to the tempo of the record, whereby the sound will continue to be reproduced after the recorder magnet has ceased to function.
5. A device for reproducing the recorded sound from a plurality of phonograph records played with short time intervals between them, so that the reproduced sound will be continuous, comprising in combination, an automatic phonograph having a turntable, a record mounted thereon, means for rotating the turntable, an electric pick-up operatively associated with the record, and means for lifting the pick-up and substituting another record for the one just finished, means for reproducing the sounds in unbroken sequence and at a slower tempo consisting of a constantly moving magnetizable wire record, a recorder magnet mounted adjacent the wire for relative movement therewith, means for energizing the recorder magnet by current from the electric pick-up, comprising a circuit containing an amplifying device, a take-off magnet positioned adjacent the wire record and spaced from the recorder magnet in the direction of movement of the wire, means for increasing the distance between the recorder magnet and the take-off magnet along the wire to decrease the tempo of the electric current induced in the take-off magnet relative to that of the electric pick-up, a loud speaker, and means for energizing the loud speaker from the take-off magnet comprising a circuit containing a power amplifier.
